UNITED STATES PATENT OFFICE.

OSCAR A. HANSON, OF ROCKFORD, ILLINOIS.

GAS RANGE.

Application filed May 20, 1925, Serial No. 31,579. Renewed October 6, 1928.

This invention relates to improvements in gas ranges and its object is to provide a gas range including means whereby the gas-supply valve may be opened by placing a 5 cooking vessel, or the like, upon the table of the range; said gas-supply valve normally remaining yieldingly closed.

A further object is to provide locking means that may be detachably secured to 10 said gas-supply valve to positively retain the same in open position when desired.

A further object is to provide a gas range that is economical in the use of fuel, simple in construction, of few parts and efficient in 15 operation.

With the foregoing and other objects in view the invention consists in the combination and arrangement of parts to be herein-after fully described, particularly pointed 20 out in the appended claim and illustrated in the accompanying drawings which form a part of this application and in which—

Fig. 1 is a view of the gas range in side elevation.

Fig. 2 is a top plan view of the table and burner.

Fig. 3 is an enlarged fragmentary sectional view illustrating a gas burner shield employed.

Fig. 4 is an enlarged fragmentary sectional view of one of the supporting legs of the range table.

Like reference characters denote corresponding parts throughout the several views.

The reference numeral 1 denotes the top or table of the range supported upon legs 2 of hollow construction, said legs telescoping 35 into the sleeves 3 and terminating in flared 40 heads 4 that rest upon the expansion coil springs 5 arranged within said sleeves. Posts 6 extend through said sleeves, springs 5 and legs, and the enlarged bases 7 of said posts being disposed at the lower ends of 45 said sleeves receive the lower ends of the springs 5. The springs 5, then, carry the weight of the legs and table and yieldingly retain the table at a predetermined height above the sleeves.

A span bar 8 extends across the table, just 50 below the top, and is secured to the sides thereof, a pitman 9 connecting said span bar to one end of the bell-crank-lever 10 that is fulcrumed upon pin 11 carried by 55 the casting 12 arranged upon the floor. A reach rod 13 connects the opposite end of

the bell-crank-lever to the gas-supply valve 14 arranged in the service pipe 15 that is tapped into the main gas pipe 16 provided with the control valve 17, said service pipe 15 being connected by the flexible pipe 18 to the stem 19 of the H-type burner 20 formed with the perforations 21, and supported by the table 1.

When a weight, such as a cooking utensil 65 or the like, is placed upon the table 1 in the usual manner it will sufficiently depress the same, thus contracting the spring 5, to cause the bell-crank-lever and reach rod 10, 13 to open the gas-supply valve 14 admitting gas 70 to the burner. An ordinary pilot (not shown) is provided in connection with this burner in the usual manner. When the cooking utensil is removed from the table 1 the latter will again resume its normal position through the return action of the spring 5 thus causing the bell-crank-lever and reach rod to close the valve 14.

A shield 22 inverted-dish shaped is supported upon legs 23 immediately above the 80 central portion, or cross bar, of the H-shaped burner. In the event that the contents of the cooking utensil should boil over the shield will protect that portion of the burner covered thereby from such contents 85 thus preventing the same from extinguishing the gas at points directly therebeneath. Should the said overflow from the cooking utensil evaporate from the heat of the burner or pass therefrom otherwise and again permit escape of the gas from all of the perforations of the burner this gas will immediately be ignited by the shielded flame beneath the member 22.

A metal yoke or bracket 24 is secured to 90 and depends from the main gas pipe 16 and carries a push button 25 having a hooked end 26, said button having secured thereto a collar 27 to which one end of the coil spring 28 is secured that encircles said button and abuts the said yoke. The purpose of 95 the spring being to yieldingly retain the button in an adjusted position relative to the yoke, the hooked end 26 of said button being adapted for releasable engagement 100 with the valve 14, in the open position of the same, to retain said valve open. The push button, which may be rotated as well as pushed inwardly, is manually placed in engagement with the valve when it is desired 105 said button should function. It is manually disengaged from said button when

desired. Ordinarily the push button does not function as the ordinary operation of the table will not cause engagement of the said button and the gas-supply valve.

5. What is claimed is:—

In a gas range, a square table, sleeves below the corners thereof, legs depending from the corners of said table into said sleeves, expansion coil springs within said sleeves 10 yieldingly supporting said legs in a predetermined position relative to said sleeves, a burner carried centrally of said table, a service pipe connecting said burner and the gas supply, said service pipe comprising a flexible portion, a gas supply valve in said service pipe beyond said flexible portion with respect to said table, a bell-crank-lever dis-

posed centrally of and beneath said table, a pitman connecting said bell-crank-lever and table, a reach rod connecting said bell-crank-lever and gas supply valve for normally opening and closing the same, and means for yieldingly retaining said gas supply valve in wide open position and arresting the movement of said reach rod and connections, said means comprising a hook capable of engagement with said gas supply valve but yieldingly retained out of operative association therewith, all substantially as and for the purpose set forth. 20 25 30

In testimony that I claim the foregoing as my own I have hereto affixed my signature.

OSCAR A. HANSON.
